(57) **CLAIM**

The ornamental design for an electrical connector, as shown and described.

DESCRIPTION

FIG. 1 is a front elevation view of an electrical connector, showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top plan view thereof showing cross section lines;

FIG. 8 is a top plan view thereof showing other cross section lines;

FIG. 9 is a cross sectional view thereof, taken along lines 9—9 in FIG. 7;

FIG. 10 is a cross sectional view thereof, taken along lines 10—10 in FIG. 8;

FIG. 11 is a top, front, and right side perspective view thereof, and,

FIG. 12 is a bottom, rear and right side perspective view thereof.
